US00D833272S

(12) **United States Design Patent** (10) **Patent No.:** **US D833,272 S**
(45) **Date of Patent:** **** Nov. 13, 2018**

(54) **FOOD CONTAINER**

(71) Applicant: **North American Robotics Corporation**, San Francisco, CA (US)

(72) Inventors: **Matthew Udomphol**, San Francisco, CA (US); **Elvine Pineda**, San Francisco, CA (US)

(73) Assignee: **North American Robotics Corporation**, San Francisco, CA (US)

(**) Term: **15 Years**

(21) Appl. No.: **29/555,101**

(22) Filed: **Feb. 18, 2016**

Related U.S. Application Data

(63) Continuation of application No. 29/521,542, filed on Mar. 24, 2015, now Pat. No. Des. 752,971.

(57) **CLAIM**

We claim the ornamental design for a food container, as shown and described.

DESCRIPTION

FIG. 1 is a top isometric view of a first embodiment of the food container.

FIG. 2 is a bottom isometric view of the first embodiment of the food container.

FIG. 3 is a plan view from the top of the first embodiment of the food container.

FIG. 4 is an elevation view from the side of the first embodiment of the food container.

FIG. 5 is a plan view from the bottom of the first embodiment of the food container.

FIG. 6 is a top isometric view of a second embodiment of the food container.

FIG. 7 is a bottom isometric view of the second embodiment of the food container.

FIG. 8 is a plan view from the top of the second embodiment of the food container.

FIG. 9 is an elevation view from the side of the second embodiment of the food container; and,

FIG. 10 is a plan view from the bottom of the second embodiment of the food container.

The broken lines illustrate portions of the food container and form no part of the claimed design.

1 Claim, 4 Drawing Sheets
